W. D. MANLY,
WIRE STRETCHING TOOL,
APPLICATION FILED OCT. 25, 1915.

1,352,983.

Patented Sept. 14, 1920.

Fig. 2.

Inventor:
Walter D. Manly.
J. Wallster Stevenson, Jr.
Atty.

UNITED STATES PATENT OFFICE.

WALTER D. MANLY, OF SHACKLEFORD COUNTY, TEXAS.

WIRE-STRETCHING TOOL.

1,352,983.

Specification of Letters Patent. Patented Sept. 14, 1920.

Application filed October 25, 1915. Serial No. 57,709.

To all whom it may concern:

Be it known that I, WALTER D. MANLY, a citizen of the United States of America, and a resident of the county of Shackelford, 5 in the State of Texas, have invented a new and useful Improvement in Wire-Stretching Tools, of which the following is a specification.

My invention relates to tools for stretching wire, and in particular for stretching 10 barbed wire for fences.

The object of my invention is to produce a simple tool, easily manufactured and readily taken apart, which can be conveniently 15 carried by one man, and with which he can stretch wire to the proper tension and readily fasten same, said tool being also adapted to be used in cutting wire and removing staples. And to this end my invention 20 consists of the novel arrangement of parts as herein described and specifically pointed out in the claims.

Referring now to the drawings which are a part of this specification,

25 Figure 1 is a perspective view of my improved tool, showing its use in connection with a fencepost or other stationary abutment, and further showing the chain and grip connected to the other end of the wire, 30 as is done when the tool is used to join two ends of wire.

Fig. 2 is an end view in cross section on the line A—A of Fig. 1, showing the arrangement of the wires when two ends are 35 being joined together.

Fig. 3 is a cross section showing the preferred form of winding drum.

Fig. 4 is a similar view showing a modified form of winding drum.

40 My device consists principally of a round metal rod or stock 10, having substantially the shape of a bit stock, the outer end being prolonged. It is provided with the usual revolvable end member 11, the bowed part 12 and the revolvable hand grip 13.

At one angle of the straight part and bowed portion I place the pronged claw 14, integral with said stock, which may be used for extracting staples. The end of the stock 50 at 15 is sharpened to a flat screw driver or chisel point, which may be used in connection with a hammer for cutting the wire when necessary.

Near this outer end I provide a member 55 16, having a hole through which the stock

10 passes so that it is revolvable about the stock, and held in place on the stock by cotter pins 18 passing through holes in the stock. This member 16 is provided at each end with prongs 17, adapted to sink into a 60 wooden post 20 when pressed thereagainst.

Along the stock 10 between the pronged member 16 and the bowed portion 12 I place a drum 21 upon which to wind the wire. This drum I have shown in my preferred 65 form as in Fig. 3 as mounted revolvably on the stock 10 and provided with a radial hole 25 alining with a diametrical hole 26 through the stock 10, these holes being of such size that the end of the wire to be 70 wound, or a nail, may be inserted into them so as to lock the drum against rotation, and at the same time permit the drum to be readily removed from the stock 10, as would be desirable when the stock was to be used to 75 wind the wire around without the drum, or when changing to a drum of different size.

I have, however, shown in Fig. 4 an alternative construction, wherein the drum 21 is keyed to the stock, and is provided with 80 a radial hole 28 to receive the end of the wire.

In either case the outer surface of the drum is concaved to provide for winding the wire around it.

85 The clevis 27 is revolvably mounted on the stock 10 and arranged so as to straddle the drum 21, and held in place on the stock by cotter pins 29 passing through holes in the stock. These serve to hold both the clevis 90 and drum in place on the shaft.

The clevis is so shaped as to provide ample space for the wire which is coiled about the drum 21. At its middle point is fastened a chain 32, and a turnbuckle 33, or 95 other means allowing for rotation of the chain may be provided. At the end of this chain is a locking dog grip 34, or other suitable means for taking hold of one of the wires to be stretched.

100 It will be observed that the pronged member 16, the drum 21 and the clevis 27 can each and all be readily removed from the stock 10 by removing the cotter pins 18 and 29.

105 In the operation of my improved device I take the end 51 of the wire to be stretched 50 and insert same into holes 25 and 26, thereby locking the drum 21 on the stock 10, and turn the stock 10 so as to wind the wire 110.

50 about the drum 21. In stretching the wire to fasten on a post, as 20, I let the prongs 17 of the pronged member 16 press against the post, and bear against the outer 5 end of the stock 10 while turning same in such a way as to hold the device against the tension of the wire.

In joining two ends of wire together before I insert the end 51 into the holes 25 10 and 26 I pass same through a loop 41 which I provide at the end of wire 40, and grip the wire 40 with the locking dog grip, as at 42. Then as I turn the stock to stretch the two wires, the stress of one balances the 15 stress of the other, and the loop 41 slips along wire 50, so that when sufficiently tightened I can bend back part of wire 50 between the drum and loop 41 with pliers or other suitable means so as to hold the 20 two ends of wire together until I can unwind enough of wire 50 from the drum to make a loop so that the two wires are fastened together.

It is obvious that many modifications 25 may be made in my device, within the scope of my invention, as defined in the claims, and I therefore do not wish to be limited to the precise structure shown.

What I claim as new, and desire to secure 30 by Letters Patent of the United States, is:

1. In a device of the class described, a shaft, a drum loosely mounted on said shaft and removable therefrom, said shaft adapted for winding wire about the portion 35 from which the drum is removed, means on said portion of the shaft for holding the end of the wire, similar means on said drum, such means cooperating so that the drum may be locked against relative rotation by the insertion of the end of the wire to be wound, and a clevis straddling said 40

drum and adapted to hold the device against the tension of the wire.

2. In a device of the class described, a shaft, a drum loosely mounted on said shaft and removable therefrom, said shaft and drum provided with alining radial holes, and a clevis straddling said drum and adapted to hold the device against the tension of the wire. 50

3. In a device of the class described, a shaft, a drum loosely mounted on said shaft and removable therefrom, said shaft adapted for winding wire about the portion from which the drum is removed, means on said portion of the shaft for holding the end of the wire, similar means on said drum, such means cooperating so that the drum may be locked against relative rotation by the insertion of the end of the wire to be wound, and a clevis removably mounted on said shaft and straddling said drum and adapted to hold the device against the tension of the wire. 55

4. A device for stretching wire, consisting 60 of a shaft, means at one end for rotating said shaft by hand and arranged for the application of transverse pressure, a drum for winding wire loosely mounted on said shaft, said shaft and drum provided with 65 alining radial holes, a clevis straddling said winding drum and adapted to hold the device against the tension of the wire, and a member mounted elsewhere on the shaft 70 adapted to impinge against an abutment, said drum, clevis, and impinging member being each removable from said shaft, without affecting the means of rotation of same. 75

In testimony whereof I have signed the foregoing specification.

WALTER D. MANLY.
